TRAVELING VALVE

John L. Anderson and John C. Wells, Burk-
burnett, Tex., assignors to Magnolia Petroleum
Company, Dallas, Tex., a corporation of Texas

Application May 10, 1930. Serial No. 451,214

9 Claims. (Cl. 103—220)

This invention relates to pumps, more particularly to pumps adapted to remove oil and the like from wells, and especially to traveling or pumping valves adapted to operate in the working barrels of such pumps.

Heretofore, in oil pumps, particularly those which have been used to pump oil containing floating sand and other foreign matter from wells, the arrangement or construction of the traveling or pumping valves adapted to operate in the working barrels of the pumps has generally been such that it has been necessary to frequently remove the valves from the working barrels to remove the sand trapped therein, this being due 15 to the relatively small capacity of the sand traps provided in the valves, and to replace one or more of the valve oil cups which had become prematurely worn because of insufficient lubrication. The frequency of these removals depended, of course, upon the particular construction of the traveling or pumping valves employed in the pumps, but it has generally been great enough to materially lower the efficiency of the pumps with which they are used and to increase the 20 cost of maintenance and operation thereof.

This invention contemplates the provision of a traveling or pumping valve for a pump adapted to pump oil and the like containing floating sand or other foreign matter from wells, which is characterized by the fact that the valve is provided with a relatively large chamber or trap in which the sand and the like is trapped, and by the fact that the valve oil cups are so arranged on the valve that the cup subjected to the greatest wear will be adequately lubricated to materially prolong its life, and when this cup finally wears and permits the passage of sand and the like thereby, another cup will prevent the accumulation of such foreign matter at points where its presence would be harmful to the valve and its parts, whereby the frequency of the removals of the valves necessary for the replacement of worn oil cups and the removal of the sand trapped therein is diminished and the general operating 45 efficiency of the valve is increased.

Other characteristics, features and objects of the invention will be apparent from the following description taken in connection with the accompanying drawing forming a part of this specification in which:

Fig. 1 is a view in elevation of a pumping or traveling valve embodying the present invention, the valve being shown in a working barrel which is shown in section, and

Fig. 2 is a longitudinal sectional view of the valve and working barrel.

The objects of the invention are attained, in general, by causing the oil and entrained sand to flow from the working barrel directly into the sand trap in the valve and by causing the oil

which is being pumped from the well to come in contact with the interior wall of the working barrel both below and above the oil cup on the traveling valve subjected to the greatest wear.

Referring to the drawing, 10 represents a working barrel in which the traveling valve embodying the present invention is adapted to operate. The traveling valve comprises a connecting head 11, having a plurality of apertures 12 therein, a section 13 having a plurality of apertures 14 in the wall thereof, a tubular member 15 suitably connected to the section 13 and having a plurality of apertures 16 in the upper portion thereof, as shown, a section 17 similar to section 13 and having apertures 18 therein, a valve section 19 provided with a pin 20 arranged transversely thereof and a tubular member 21. These parts are adapted to be threaded together as shown, or connected by other suitable means.

As shown, a plurality of oil cups 22 are mounted on tubular member 21, suitably spaced by spacer rings 23, and are retained on the member 21 by nuts 24, or otherwise. Valve section 19 has a ball valve 25 therein which is adapted to seat on seat 26 formed in the upper end of member 21, and pin 20 is adapted to limit the upward movement of the ball 25. As shown, an oil cup 27 is provided at the upper end of valve section 19 and an oil cup 28 is mounted on the traveling valve at the upper end of the tubular member 15.

The outside diameter of tubular member 15 is preferably sufficiently smaller than the inside diameter of the working barrel 10, to provide an annular space 29 between the working barrel and the tubular member as shown. Tubular member 29 together with section 17 form a sand trap 30 in the valve. A sucker rod 31 connects the traveling valve to a suitable source of power such as a walking beam or the like at the surface.

In the operation of the working valve, on the downward stroke thereof, oil from the well which has previously passed a standing valve (not shown) in the working barrel, is forced into the lower part of the traveling valve through tubular member 21, past ball check valve 25 into section 17 and through apertures 18 therein into space 29. From the space 29, the oil and any entrained sand or other foreign matter is forced into sand trap 30 through aperture 16, where the greater part of the sand and the like will be separated from the oil and will settle in the bottom of the sand trap as at 32. From the sand trap 30, the oil is forced through apertures 14 in section 13 and through apertures 12 in connecting head 11 into the working barrel above the oil cup 28, whence it will be forced to the surface upon the upward stroke of the traveling valve, during which upward movement, ball check valve 25 will be seated on its seat 26 and thus prevent oil flowing past the valve as will be understood.

With this arrangement, it will be apparent that the oil from the well comes in contact with the interior wall of the working barrel both below and above the oil cup 28 which is the cup on the 5 traveling valve subjected to the greatest amount of wear. This cup is therefore adequately lubricated and its life will thereby be materially prolonged. And when this cup 28 finally wears to such an extent that sand and the like pass the 10 cup, cup 27 will take care of the sand and prevent it from reaching the cups 22. Moreover, the sand is prevented from accumulating on cup 27 by reason of the fact that the oil flowing through apertures 18 will dislodge any sand 15 which has accumulated on that cup and carry it into the sand trap 30. And, since the oil is caused to flow from the working barrel directly into the sand trap 30, or from the zone of the sand trap and exterior thereto rather than through 20 the bottom of the sand trap, as has heretofore generally been the case, the capacity of the sand trap is materially increased.

For these reasons, it will be apparent that the frequency of the removals of the traveling valve 25 for replacement of worn oil cups and removal of the sand from the sand trap is greatly diminished and the general operating efficiency of the valve is increased.

Although the invention has been shown and described as particularly well adapted to the pumping of oil from wells, it is evident that it is equally well adaptable to the pumping of other liquids.

The form of the invention herein disclosed is to be considered as a preferred form only and it is understood that the invention is not to be limited 35 except by the scope of the appended claims.

What we claim is:

1. A traveling valve adapted to operate in a working barrel to pump oil from a well, said valve 40 having a sand trap and a portion formed to provide a space between the valve and the working barrel, and means causing oil to flow into said space and from said space into the sand trap.

2. A traveling valve adapted to operate in a 45 working barrel to pump oil from a well, said valve having a sand trap formed to provide a space between the working barrel and the wall of the sand trap, and means causing oil to flow from said space into the sand trap.

3. A traveling valve adapted to operate in a working barrel to pump oil from a well, said valve having spaced oil cups, a sand trap between the cups, the wall of the sand trap being formed to provide a space between the working 55 barrel and said wall, and means causing oil to flow from the working barrel below said valve into said space and from said space into the sand trap.

4. A traveling valve adapted to operate in a 60 working barrel to pump oil from a well, said valve having spaced oil cups, a sand trap intermediate the oil cups, the wall of the sand trap being formed to provide a space between the working barrel and the said wall, the valve having an aperture and a passage below the sand trap and an aperture in the wall of the sand trap, whereby oil is forced from the working barrel below the valve into said passage, through 65 the first mentioned aperture into said space and from said space through the second mentioned aperture into the sand trap.

5. A traveling valve adapted to operate in a working barrel to pump liquid from a well, said

valve having a sand trap spaced within the working barrel and having an annular free space exterior to the sand trap, the wall of the sand trap having a plurality of apertures therein whereby the sand trap is directly connected with the working barrel and means causing liquid to flow from the working barrel into the sand trap through the apertures.

6. A traveling valve adapted to operate in a working barrel to pump oil from a well, said valve having spaced oil cups, a sand trap intermediate the oil cups, the wall of the sand trap being formed to provide a space between the working barrel and the said wall, the valve having a plurality of apertures and a passage below the sand trap and a plurality of apertures in the wall of the sand trap, whereby oil is forced from the working barrel below the valve into said passage, through the first mentioned apertures into said space and from said space through the second mentioned apertures into the sand trap.

7. A traveling valve adapted to operate in a working barrel to pump liquid from a well, comprising spaced portions, each having a passage therein and an oil cup adapted to engage the interior of the working barrel, and a sand trap intermediate said spaced portions, the wall of the sand trap being formed to provide a space between the trap and the working barrel, one of said portions having an aperture through which liquid flows from said portion into said space and the wall of said trap having an aperture through which liquid flows from said space into the sand trap.

8. A traveling valve adapted to operate in a working barrel to pump liquid from a well comprising lower, upper and intermediate portions, the lower and upper portions each having a passage therein and an oil cup adapted to engage the interior of the working barrel, said lower portion having a check valve controlling the passage therein, the intermediate portion comprising a sand trap, the wall of which is spaced from the interior wall of the working barrel to provide a space through which liquid from the well is adapted to flow, said lower portion having an aperture connecting the passage therein and said space, the sand trap having an aperture in the wall thereof through which liquid flows from said space into the sand trap.

9. A traveling valve adapted to operate in a working barrel to pump liquid from a well comprising lower, upper and intermediate portions, the lower and upper portions having a passage therein and an oil cup mounted thereon adapted to engage the interior of the working barrel, the lower portion having a check valve adapted to control the passage therethrough, the intermediate portion of the valve comprising a sand trap formed to provide a space between the wall of the sand trap and the working barrel, said space extending between the oil cups on the upper and lower portions, the lower portion having an aperture through which liquid is adapted to flow from the passage therein into said space, the wall of the sand trap having an aperture therein adjacent the upper portion thereof and adjacent the oil cup on the said upper portion through which aperture liquid is adapted to pass from said space into the sand trap.
